UNITED STATES PATENT OFFICE

NEIL D. MUNN, OF DRESDEN, ONTARIO, CANADA.

STEAM-GENERATING BLACKSMITH'S FORGE.

931,951.

Specification of Letters Patent. Patented Aug. 24, 1909.

Application filed October 31, 1908. Serial No. 460,502.

To all whom it may concern:

Be it known that I, NEIL D. MUNN, of the town of Dresden, county of Kent, Province of Ontario, Canada, blacksmith, have 5 invented certain new and useful Improvements in Steam-Generating Blacksmiths' Forges.

The object of my invention is to provide means whereby the heat generated in an 10 ordinary blacksmith's forge may be rendered available to operate a small steam engine for general use in a blacksmith's shop, and I attain this object by the mechanism hereinafter fully described and then definitely claimed.

Figure 1 is a vertical side view of my device as applied to an ordinary blacksmith's forge. Fig. 2 is a front view of the boiler with the hood shown in Fig. 1 removed. 20 Fig. 3 is a plan view of the hot water twyer and fire pot. Fig. 4 is a cross section on line *a—a* Fig. 3. Fig. 5 is a cross section on line *f—f* Fig. 3. Fig. 6 is lower guide ring shown in Figs. 4 and 5. Fig. 7 is upper 25 guide half ring shown in Figs. 4 and 5.

Like letters of reference indicate similar parts in the various figures.

In Fig. 1 *Y* is a base piece for supporting the fire pot, boiler etc., which may be made 30 of metal or of brick work or other material, as may be desired. *U* is the firepot shown more particularly in Figs. 4 and 5. This fire pot is surrounded by the twyer iron surrounding the fire pot and forming water 35 spaces *W* as indicated in Figs. 4 and 5. This twyer iron is divided by partition *d* shown by the Figs. 3 and 5, which separates the entrance into the water space *W* of the pipe *B* and the pipe *C* hereafter referred to. 40 *G* is a blow off valve communicating with the interior of the water space surrounding the fire pot. *O* is a housing formed below the twyer iron and fire pot with a hinged bottom *P¹* hinged at *p* to the housing. This 45 carries a plunger rod *P* which passes through the half guide ring *M¹*, shown in Fig. 7, and the guide ring *M*. The half ring is opposite the entrance of the air pipe *L* from the bellows, so that the air may pass 50 more freely up through the top *K* of the plunger rod *p* and through the orifices *k* formed therein to the bottom of the fire pot. The top *K* with orifices is shown particularly in Fig. 3.

Fig. 4 shows the hinged door *P¹* closed

and holding the top *K* of the plunger rod up in position to support the fire in the fire pot.

When it is desired to dump ashes and cinders the lever arm *N* shown in Fig. 5 is pulled down, as indicated, thus opening the door so as to allow the escape of the ashes etc. When pressure is removed from this lever arm the counterweight *b* on the extension arm *b¹* reseats the hinged base door *P¹* and forces the top *K* of the plunger rod up 65 into position in the base of the fire pot.

In Fig. 2 it is further seen that a boiler *V* preferably of the vertical type and widening toward its upper end is supported on the base pieces in proximity to the fire pot. This 70 boiler is provided with flues *F*, shown in Figs. 1 and 2, which carry the products of combustion from the fire pot up through the boiler and into the smoke pipe *X*. This boiler is provided with water gage *R* and 75 steam gage *S*. *A* is a cold water feed pipe discharging into the bottom of the boiler while *B* is a pipe which carries the water from the boiler to the water space *W* below the fire pot. This water becomes intensely 80 heated in passing around the water space to the partition *d*, and the heated water and steam is carried up through the pipe *C* discharging into the top of the boiler as indicated. *D* is a safety valve on this hot water 85 pipe *C* while *E* is the steam feed pipe to the engine. *H* is a hood pivotally connected to the front of the boiler and is situated over the fire pot. It is held in position by a cross rod *J¹* which is supported by the hooks *J* 90 shown in Figs. 1 and 2. This hood *H* can either be removed altogether from the hook or it can be tilted up into position so that the hook *h* engages with the top of the boiler. It will thus be seen that the water which 95 passes through the cold water feed pipe through the bottom of the boiler is conveyed thence down the pipe *B* to the water space formed between the twyer iron and the fire pot where the water becomes intensely heated. It is thence carried up the pipe *C* adjoining the partition *d* and the steam and hot water is discharged into the top of the boiler. This heated water circulates freely through 100 the boiler and is further heated by means of the flues *F* which are formed in the boiler as indicated.

By means of these improvements it will be seen that I am able to supply power for a small engine to run other necessary mech- 110

anism connected with a blacksmith shop by utilizing the heat supplied by the ordinary blacksmith's forge.

What I claim as my invention is:—

- 5 1. In a steam generating blacksmith's forge, the combination with the fire pot, of a twyer jacket surrounding the fire pot and forming a water space, a boiler provided with flues leading to the smoke pipe, a cold water inlet pipe at the bottom of the boiler, a pipe communicating between the bottom of the boiler and the water chamber in the twyer jacket, a hot water pipe leading from the water chamber in the twyer jacket to the 10 top of the boiler, a partition formed in the twyer jacket between the pipe openings, and a steam feed pipe leading from the top of the boiler, substantially as specified.
- 15 2. In a steam generating blacksmith's forge, the combination with the fire pot, of a partitioned twyer jacket surrounding the 20

fire pot and forming a water space, a blow off valve from the water space, a boiler provided with flues leading to the smoke pipe, a hood over the fire place pivotally connected 25 to the front of the boiler, a cold water inlet pipe at the bottom of the boiler, a pipe communicating between the bottom of the boiler and the water chamber in the twyer jacket, a hot water pipe leading from the water chamber 30 in the twyer jacket to the top of the boiler, a partition formed in the twyer jacket between the pipe openings, a safety valve at the top of the hot water pipe, and a steam feed pipe leading from the top of 35 the boiler, substantially as specified.

Dresden, Ont. 24th October 1908.

NEIL D. MUNN.
